(57) **CLAIM**

I claim the ornamental design for a light bar for an emergency vehicle, as shown and described.

DESCRIPTION

FIG. 1 is a perspective view of a first embodiment of a light bar for an emergency vehicle according to the present invention.

FIG. 2 is a top plan view of the light bar for an emergency vehicle of FIG. 1.

FIG. 3 is a front elevational view of the light bar for an emergency vehicle of FIG. 1, with the rear elevational view thereof being identical to the view of FIG. 3.

FIG. 4 is a side elevational view of the light bar for an emergency vehicle of FIG. 1, with the other side elevational view thereof being identical to the view of FIG. 4.

FIG. 5 is a perspective view of a second embodiment of a light bar for an emergency vehicle according to the present invention.

FIG. 6 is a top plan view of the light bar for an emergency vehicle of FIG. 5.

FIG. 7 is a front elevational view of the light bar for an emergency vehicle of FIG. 5, with the rear elevational view thereof being identical to the view of FIG. 7; and,

FIG. 8 is a side elevational view of the light bar for an emergency vehicle of FIG. 5, with the other side elevational view thereof being identical to the view of FIG. 8.
